UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

HOISTING MECHANISM

Application filed February 18, 1927, Serial No. 169,324. Renewed August 11, 1930.

This invention relates to hoisting mechanisms and more especially to the portable type of hoist.

Portable hoisting mechanisms, particularly those of the double drum type, are largely used for drag scraper work and for what is called "slushing" in metal mines, in the operation of which a scraper will be dragged back and forth through the ore or other material to be handled. In hoisting mechanisms such as herein disclosed, a reversible type of motor is used with suitable means to drive one drum or the other automatically in accordance with the direction 10 of motor rotation and this causes the drums to be reversely rotatable.

An object of this invention is to provide an improved double drum hoist wherein the winding drums are alternatively driven automatically in accordance with the direction of motor rotation. Still another object of this invention is to provide such a hoisting mechanism wherein the drums are yieldably connected to the driving motor, this connection being effected automatically in accordance with the direction of motor rotation. Yet another object of this invention is to provide an improved double drum hoisting mechanism having a single reversible driving motor and separate driving connections between the driving motor and each of the drums, each of these driving connections including a reaction member adapted to be held stationary or released automatically in accordance with 25 the direction of motor rotation. These and other objects of this invention will, however, subsequently more fully appear.

In the accompanying drawings, there are shown for purposes of illustration two forms 40 which the invention may assume in practice.

In these drawings,—

Fig. 1 is a central longitudinally extending vertical sectional view through improved hoisting mechanism illustrating one embodiment of my invention, parts being shown in elevation.

Fig. 2 is a transverse vertical sectional view taken on line 2—2 of Fig. 1.

Fig. 3 is a transverse vertical sectional view 50 taken on line 3—3 of Fig. 1.

Fig. 4 is a side elevational view of a hoisting mechanism of the type shown in Fig. 1 but illustrating a modified form of automatic control for the drums, the view being shown partially in section to illustrate details of construction. 55

Fig. 5 is a transverse vertical sectional view taken on line 5—5 of Fig. 4.

Fig. 6 is a transverse vertical sectional view taken on line 6—6 of Fig. 4.

In the illustrative construction shown in Figs. 1 to 3 there is shown a hoisting mechanism generally designated 1 having a frame 2 which has secured thereto by screws 3 upstanding end supports 4 and 5. As shown, secured by bolts 6 to the frame 2 at one end thereof is a supplemental base frame 7 and this base frame forms a support for a motor 8 which is herein of the reversible electric type, although it is obvious that any other suitable type of reversible motor may be utilized if desired. The motor 8 is secured to the frame 7 by screws 9. Secured to the armature shaft 10 of the motor is a motor pinion 11 and this pinion meshes with an internal gear 12 keyed at 13 to one end of a longitudinally extending horizontal driving shaft 14, herein preferably arranged parallel with the motor axis and journaled at its opposite ends in spaced alined ball bearings 15 and 16 70

carried respectively within the end supports 4 and 5. To prevent access of dirt or other foreign substances to the gears 11 and 12 there is provided a suitable housing 17 secured as by screws 18 to the end support 4, 75 the housing having a detachable cover plate 19 to permit access to these gears. As illustrated, secured as by keys 20 adjacent the opposite ends of the shaft 14 are spur pinions 21 and 22. In accordance with this 80

illustrative embodiment of the invention, the pinions 21 and 22 constantly mesh respectively with planetary drum driver gears 23 and 24, each of which is journaled on ball bearings 25 carried by a stub shaft 26. The 85 shafts 26 are respectively carried by coaxial relatively rotatable winding drums 27 and 28, as for instance, a haulage drum and a tail rope drum; and these drums are disposed between the supports 4 and 5 and are each 90 95

5 journaled on ball bearings 29 and 30 supported by the transmission shaft 14. Suitably connected to the drums 27 and 28 respectively, are usual drag line cables or ropes 31. It will be noted that in this instance the 10 drum driver gears 23 and 24 constantly mesh respectively with internal reaction gears 32 and 33 suitably secured to end members 34 and 35, respectively. Each reaction gear is 15 provided with a hub portion 34^a suitably carried by its respective support 4, or 5 and journaled in roller bearings 35^a. These hub portions also form supports for the ball bearings 15, 16. Each of the reaction gears 32 and 33 is externally grooved at 36; and suitable 20 brake bands 37 of improved form to be later described cooperate with the bottom surfaces of these grooves.

25 As clearly shown in the drawings, the 20 brake bands 37 are identical in structure, but are reversely positioned, so that when one is applied the other is automatically released, and consequently when one of the reaction gears is held stationary the other is free to 25 rotate. These brake bands are of the automatic type, and each has a loop portion at one end thereof connected at 38 to the end supports of the frame. A transverse pin 39 is carried by upstanding lugs formed on the 30 frame 2, and pivotally connected to the pin 39 is an eye bolt 40 upon which the other end 41 of the band is slidably connected. Springs 42 are disposed on the bolts 40 to constantly force the ends 41 of the bands 37 outwardly 35 against a nut 43 threadedly connected to the eye bolt; and these springs cause the bands 37 to grip the bottom surfaces of the grooves on the reaction gears when the drums tend to 40 rotate in one direction. Whenever the reaction gears rotate in the opposite direction, the gears acting against the brake bands 37 will tend to raise the free ends of the eye bolts 40 and to compress the springs 42 and thus automatically release the friction of the 45 bands upon the reaction gears. However, the brake bands 37 always have a slight tendency to resist rotation of the reaction gears and consequently the drums always tend to maintain the drag lines taut. It is obvious 50 that various types of friction devices may be used for holding the reaction gears against rotation in lieu of that shown.

55 In the operation of this form of improved hoisting mechanism, assuming that the haulage drum 27 is to be rotated and that it be desired to release the tail rope drum 28, the motor 8 is rotated in the desired direction; and consequently (see Fig. 2) the pinion 21 is rotated in a counter-clockwise direction 60 while the drum driver gear 23 is rotated in a clockwise direction; and as this gear meshes with the internal gear 32, the latter tends to rotate also in a clockwise direction; but as the gear turns in this direction, the brake 65 band 37 will automatically be applied and

consequently the reaction gear is held against rotation. During rotation of the motor in this direction (see Fig. 3) the pinion 22 will also rotate in a counter-clockwise direction, and the drum driver gear 24 will rotate in a 70 clockwise direction; and consequently the internal gear 33 with which the gear 24 meshes will also rotate in a clockwise direction, the brake band 37 controlling rotation of the reaction gear 33 being automatically released at that time, due to the swinging of the eye bolt and the compression of the coiled spring 42. It will thus be evident that when the motor is rotated in this direction the reaction gear 32 is automatically held against rotation 75 while the reaction gear 33 is automatically released; and consequently the drum 27 is driven while the drum 28 is rotatable to permit unwinding of the cable thereon. When it is desired to drive the drum 28 and to 80 unwind the cable on the drum 27, the motor 8 is reversed and consequently the reaction gear 33 is automatically held stationary by its co-operating brake band, while the brake band controlling rotation of the reaction gear 32 85 is automatically released; and consequently the drum 28 is driven, while the drum 27 is freely rotatable.

90 In the form of the invention shown in Figs. 4 to 6 the driving motor, the winding drums, and the driving connections between the motor and winding drums are identical to that described above in the first form of the invention. However, in this form of the invention a different type of mechanism is provided for controlling the reaction gears 32 and 33; and this mechanism specifically comprises ratchet teeth 44 and 45 formed respectively on the exterior of the internal gears 32 and 33, these ratchet teeth being reversely 95 arranged for a purpose to be later described. Disposed longitudinally of the hoisting mechanism, and below the winding drums is a rocker shaft 46 suitably journaled at its ends 100 within the frame 2. Secured to the ends of this shaft are pawls or dogs 47 and 48 which are respectively adapted to cooperate with the ratchet teeth 44 and 45. These pawls 47 and 48 are so arranged on the shaft 46 that 105 when one of the same engages its cooperating ratchet teeth, the other pawl is disengaged. It is obvious, however, that other forms of automatic devices may be utilized in place of the pawls and rocker arm described above, for instance separate spring 110 pressed pawls constantly engaging the ratchet teeth, or a spring controlled crank arm secured to the rocker arm to automatically throw the pawls when the crank passes its vertical center.

115 In the operation of this form of the invention, when the motor 8 is driven in one direction, one of the pawls is automatically thrown out from its cooperating ratchet teeth, while the other pawl is automatically thrown into

engagement with its cooperating ratchet teeth, this being due to the inclined outer surfaces of the ratchet teeth which act as cams for forcing the pawls from their engaged position when the reaction gears are rotated in one direction. For instance, when the pinions 21 and 22 as shown in Figs. 5 and 6 are rotated in a counter-clockwise direction, the drum driver gears 23 and 24 are rotated in a clockwise direction and the reaction gears 32 and 33 with which the drum driver gears respectively mesh are also rotated in a clockwise direction, and consequently (see Fig. 6) the inclined surfaces of the ratchet teeth 45 force the pawl 48 out of engagement therewith, while the pawl 47 swings into engagement with the ratchet teeth 44. Consequently the reaction gear 32 is positively held against rotation while the reaction gear 33 is free to rotate. The drum driver gear 23 will then roll about the internal gear 32 as a trackway and cause the drum 27 to revolve therewith. It will be evident when the motor is reversed, the pawl 47 will be automatically released from the teeth 44, while the pawl 48 will be swung into engagement with the teeth 45, thereby holding the reaction gear 33 against rotation while the reaction gear 32 freely rotates; and consequently the drum 28 will be positively driven while the drum 27 will be freely rotatable. These and other operations of this improved hoisting mechanism will be clearly apparent to those skilled in this art.

As a result of this invention it will be noted that an improved double drum hoist is provided having separate driving connections between the motor and drums, each of these connections including reaction gears which are alternatively held stationary or released automatically in accordance with the direction of motor rotation. It will further be noted that an improved double drum hoist is provided wherein the winding drums are alternatively connected to the driving motor wholly independently of manual operation of the connections, the drums being connected in driving relation with the motor automatically in accordance with the direction of motor rotation.

While I have in this application specifically described two forms which my invention may assume in practice, it will be understood that these forms are shown for purposes of illustration and that the invention may be modified and embodied in various other forms without departing from its spirit or the scope of the appended claims.

What I claim as new and desire to secure by Letters Patent is:

1. In a hoist, a reversible motor, a pair of relatively rotatable winding drums, and driving connections between said motor and each of said drums including a reaction gear, and means for alternatively holding said reaction

gears stationary automatically in accordance with the direction of motor rotation.

2. In a hoist, a reversible motor, a pair of relatively rotatable winding drums, and driving connections between said motor and each of said drums including a reaction gear, a brake band controlling rotation of said reaction gear, and means for alternatively applying and releasing said brake band automatically in accordance with the direction of motor rotation. 75

3. In a hoist, a reversible motor, a pair of relatively rotatable winding drums, and driving connections between said motor and each of said drums including a drum driver gear journaled on each drum and movable therewith during rotation thereof, an internal reaction gear with which said drum driver gear meshes, a brake band encircling said reaction gear for controlling rotation thereof, and means for alternatively applying and releasing said brake bands automatically in accordance with the direction of motor rotation. 80

4. In a hoist, a reversible motor, a pair of relatively rotatable winding drums, coaxially arranged and disposed substantially in end abutting relation, and operative driving connections between said motor and drums including a reaction member rotatably mounted at the remote ends of said drums, said driving connections including means operative for alternatively holding said reaction members stationary automatically in accordance with the direction of motor rotation. 90

5. In a hoist, a reversible motor, a pair of relatively rotatable winding drums, coaxially arranged and disposed substantially in end abutting relations, and means for alternatively connecting said drums in driving relation with said motor including separate frictional controlling means for each drum, said frictional controlling means being automatically alternatively operable in accordance with the direction of motor rotation. 105

6. In a hoist, a reversible motor, a pair of relatively rotatable winding drums, coaxially arranged and disposed substantially in end abutting relation, and operative driving connections between said motor and drums including a common driving shaft about which said drums are rotatable, driving pinions secured to said shaft at the ends thereof, driving gearing between said pinions and each of said drums including a drum driver gear journaled on each of said drums, an internal reaction gear with which each of said drum driver gears mesh, and means for holding and releasing said reaction gears automatically in accordance with the direction of motor rotation. 115

7. In a hoist, a reversible motor, a pair of relatively rotatable winding drums, and operative driving connections between said motor and drums including separate frictional con- 125

trolling means for each drum, said frictional controlling means being automatically alternatively operable in accordance with the direction of motor rotation for frictionally connecting said drums in driving relation with said motor, the driving connections for each drum including an automatically frictionally controlled reaction gear.

8. In a hoist, a reversible motor, a pair of relatively rotatable winding drums, and operative driving connections between said motor and drums including a rotatable reaction member for controlling each drum, and means for holding one of said reaction members stationary and for releasing the other member automatically in accordance with the direction of motor rotation.

9. In a hoist, a reversible motor, a pair of relatively rotatable coaxial winding drums, and operative driving connections between said motor and drums including means for alternatively connecting said drums in driving relation with said motor automatically in accordance with the direction of motor rotation, said automatic controlling means including brake bands alternatively applied and released.

10. In a hoist, a reversible motor, a pair of relatively rotatable winding drums, and operative driving connections between said motor and drums including a reaction member for each drum, and means for alternatively braking one or the other of said reaction members for holding the same stationary during drum driving automatically in accordance with the direction of motor rotation.

11. In a hoist, a reversible motor, a pair of relatively rotatable winding drums, and operative driving connections between said motor and drums including means for connecting one drum to the motor and for disconnecting the other drum therefrom automatically in accordance with the direction of motor rotation, said driving connections including an automatic brake band for controlling each drum.

12. In a hoist, a reversible motor, a pair of relatively rotatable winding drums, and operative driving connections between said motor and drums including a rotatable reaction member for each drum, and means for automatically holding one or the other of said reaction members stationary in accordance with the direction of motor rotation and at the same time automatically releasing the remaining reaction member, whereby one of said drums is automatically driven while the other drum is released automatically in accordance with the direction of motor rotation.

13. In a hoist, a reversible motor, a pair of relatively rotatable winding drums, and operative driving connections between said motor and drums including drive control means for each drum provided with a brake band controlling driving of the drum, and

means for automatically alternatively applying one or the other of said brake bands in accordance with the direction of motor rotation to effect drum rotation control automatically in accordance with the direction of motor rotation.

14. In a hoist, a reversible motor, a pair of relatively rotatable winding drums, operative driving connections between said motor and drums, the connection between each drum and said motor including a separate control member, and means for frictionally holding said control members stationary alternatively, said friction means being automatically operable to hold one or the other of said members stationary to effect driving of one of said drums automatically in accordance with the direction of motor rotation.

15. In a hoist, a drive shaft rotatable at will in opposite directions, a pair of relatively rotatable winding drums, and driving connections between said drive shaft and each of said drums including a reaction gear, and means for alternatively holding said reaction gears stationary automatically in accordance with the direction of drive shaft rotation.

16. In a hoist, a reversely rotatable drive shaft, a pair of relatively rotatable winding drums, and driving connections between said shaft and each of said drums including a drum driver gear journaled on each drum and movable therewith during rotation thereof, an internal reaction gear with which said drum driver gear meshes, and means cooperating with the periphery of said reaction gear to prevent rotation thereof in one direction automatically permitting rotation in the opposite direction, said last mentioned means operating to preclude rotation of said reaction gears in the same direction whereby opposite rotation of said drive shaft automatically effects winding operation of different drums.

17. In a hoist, a reversely rotatable drive shaft, a pair of relatively rotatable winding drums, and driving connections between said shaft and each of said drums including a reaction gear, and means for alternatively positively holding said reaction gears stationary automatically in accordance with the direction of shaft rotation.

18. In a hoist, a reversible motor, a pair of relatively rotatable winding drums, and driving connections between said motor and each of said drums including a reaction gear, and means for alternatively positively holding said reaction gears stationary automatically in accordance with the direction of motor rotation.

19. In a hoist, a reversible motor, a pair of relatively rotatable winding drums, and driving connections between said motor and each of said drums including a reaction gear, and means including teeth on said reaction

70

gears and cooperating shiftable pawls for alternatively positively holding said reaction gears stationary in accordance with the direction of motor rotation.

5 20. In a hoist, a reversely rotatable drive shaft, a pair of relatively rotatable winding drums, and operative driving connections between said shaft and drums including a rotatable reaction member for each drum, and
10 means for automatically holding one or the other of said reaction members stationary in accordance with the direction in which said drive shaft is rotated and at the same time automatically releasing the remaining reaction member, whereby one of said drums is automatically driven while the other drum is released automatically in accordance with the direction of drive shaft rotation.

21. In a hoist, a reversely rotatable drive shaft, a pair of relatively rotatable winding drums, and operative driving connections between said shaft and drums including members, one individual to the transmission of power to each drum, which when held stationary cause winding operation of their respective drums and when released for rotation permit rotation of their respective drums, and means for automatically holding one or the other of said members stationary
25 in accordance with the direction in which said drive shaft is rotated and at the same time automatically releasing the remaining one of said members.

In testimony whereof I affix my signature.
35 CHARLES F. OSGOOD.
